US00D326574S

United States Patent [19]

Albright et al.

[11] Patent Number: Des. 326,574

[45] Date of Patent: ** Jun. 2, 1992

[54] **DISPLAYER FOR CHARGED ELECTRICAL PARTICLES**

[75] Inventors: **Larry W. Albright**, 419 Sunset Ave., Venice, Calif. 90291; **Laura L. Craig**, Los Angeles, Calif.

[73] Assignee: **Larry W. Albright**, Venice, Calif.

[**] Term: **14 Years**

[21] Appl. No.: **243,933**

[22] Filed: **Sep. 12, 1988**

[52] U.S. Cl. **D6/472; D11/131; D26/104**

[57] **CLAIM**

The ornamental design for a display for charged electrical particles, as shown.

DESCRIPTION

FIG. 1 is a perspective view of a display for charged electrical particles showing our new design;

FIG. 2 is a top plan view;

FIG. 3 is a front elevational view;

FIG. 4 is a rear elevational view;

FIG. 5 is a left side elevational view;

FIG. 6 is a right side elevational view;

FIG. 7 is a bottom plan view;

FIG. 8 is a top plan view of a second embodiment of the display shown in FIG. 1;

FIG. 9 is a front elevational view;

FIG. 10 is a rear elevational view;

FIG. 11 is a left side elevational view; and,

FIG. 12 is a right side elevational view thereof.

*Fig. 1**Fig. 2**Fig. 3**Fig. 4**Fig. 5**Fig. 6**Fig. 7**Fig. 8**Fig. 9**Fig. 10**Fig. 11**Fig. 12*
